UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,988, dated December 26, 1893.

Application filed October 14, 1893. Serial No. 488,175. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design is formed of a series of leaf-like ornaments arranged in the form of a wreath with a flamboyant torch arranged vertically through the center of said wreath and attached thereto by a flowing ribbon and festoons of small circles or balls hanging from said ornaments as shown in the accompanying drawing.

What I claim is--

The design for wall paper herein shown and described.

Witness my hand this 10th day of October, 1893.

CHARLES BOOZE.
